UNITED STATES PATENT OFFICE.

THOMAS E. MURRAY AND ARTHUR V. A. McHARG, OF NEW YORK, N. Y.; SAID McHARG
ASSIGNOR TO SAID MURRAY.

ELECTRICALLY-CONTROLLED CUT-OUT.

1,120,222.

Specification of Letters Patent.

Patented Dec. 8, 1914.

Application filed July 11, 1913; Serial No. 778,444.

To all whom it may concern:

Be it known that we, THOMAS E. MURRAY and ARTHUR V. A. McHARG, citizens of the United States, residing at New York, in the county of New York and State of New York, have invented a certain new and useful Improvement in Electrically-Controlled Cut-Outs, of which the following is a specification:

The invention is an automatic electric cut-out for releasing a switch lever of the knife-type by electrically controlled mechanism. It is so constructed that upon either an overload or a failure of current on the system, the device operates automatically to open circuit by withdrawing the fuse plug or fuse plugs. The device is here shown in a three-wire system wherein a fuse plug is provided in each conductor, but obviously it may be used in one branch or both branches of a two-wire system, as preferred. For illustrative purposes it is here shown applied to the lever of the electric cut-out set forth in an application for Letters Patent, Serial No. 764,491, filed by Arthur V. A. McHarg, April 30th, 1913, and now pending.

In the accompanying drawings—Figure 1 is a side elevation of our cut-out, showing the base block in section. Fig. 2 is a plan view, with the shield broken away and the fuse plugs in section. Fig. 3 is an end elevation.

Similar numbers and letters of reference indicate like parts.

The base block 1 is preferably of refractory insulating material, such as porcelain, and has two side walls 2, 3 and two intermediate partitions so as to divide the space between said walls into three channels 4, 5, 6. Extending across said channels and passing through the walls 2, 3 and partitions are three mutually insulated superposed bus-bars 7, 8, 9.

10, 11, 12 are circuit conductors of a three-wire system connected to plates 13, 14, 15 fixed respectively in channels 4, 5, 6. Each plate has an upwardly extending projection which forms one member of a pair of contacts, the other members of said contacts being similar projections on plates 16, 17, 18, also disposed in said channels and connected respectively to said bus-bars by metal strips 19, 20, 21. It will be obvious that by inserting fuse plugs between the

pairs of contacts in the several channels, circuit will be established from bus-bars 7, 8, 9 to circuit conductors 10, 11, 12. Said fuse plugs are inserted and removed by means of a switch lever 22, which comprises a supporting bar 23, to which are secured three parallel bell crank levers, one of which, 24, is longer than the others, and an operating handle 25. Switch 22 is pivoted at 26 to the base block 1. The horizontal arms of the bell crank levers enter openings in the fuse plugs 27. The arm of lever 24 extends beyond the plug which it carries. Each plug consists of a carrier block of insulating material, having a thin upper portion over which is doubled a fuse strip 28 secured to said block. When the switch is in the position shown in Fig. 1, the fuse plugs are brought into place between the pairs of contacts in the base block channels. The switch is opened by means of handle 25 which, when swung to the right of Fig. 1, causes said fuse plugs to be simultaneously lifted out of said pairs of contacts. The cross bar 23 carries a shield 29.

The foregoing construction is more fully set forth in the aforesaid application of Arthur V. A. McHarg.

A is a metal support, having a bottom plate and, integral therewith, two vertical plates B, C. The plate C has a projecting portion D disposed at right angles to its face. Between the plates B, C is an electro-magnet coil E, a polar extremity of the core of which passes through the plate C. Supported on the projection D is another electro-magnet coil F, a polar extremity of the core of which passes through said projection. The two electro-magnets E and F have a common armature formed of two plates G, H, disposed at right angles, as best shown in Fig. 2. Said plates may be integral. The armature G, H is carried by a vertical arm I which is pivoted to swing at right angles to a short arm J in turn pivoted in a bracket K extending from plate C. On the upper part of the arm I is a shoulder L. Bearing at one end on arm I is a strong bent spring M which is coiled around the pivot of arm J and bears at its opposite end upon a fixed abutment. Connected at one end to the part H of armature G, H is a helical spring N, the other end of said spring being secured to a fixed arm O on the base block. The two electro-mag-

nets are connected in series in circuit conductor 12. Secured to switch lever 22 and to base block 1 are hooked arms 30, between which is secured a helical retracting spring P.

The operation is as follows: To establish circuit, the switch is closed. Electro-magnet F is then energized and attracts part H of armature G, H, moving pivoted arm I 10 against the pull of spring N until the shoulder L on said arm rides over and engages the extremity of the extended arm of bell crank lever 24, as shown in Fig. 1. Current also flows through electro-magnet coil 15 E, but armature G, H is prevented from moving toward said coil by the strong spring M, so long as normal current is maintained. But if an overload of current occurs, then electro-magnet E overcomes 20 spring M and attracts armature G, H in a direction at right angles to that in which said armature was previously attracted by electro-magnet F. By reason of this movement, the shoulder L is withdrawn from 25 engagement with bell crank arm 24, so that the spring P can now throw the switch lever to remove the fuse plugs from the block contacts. On the other hand, if instead of 30 an overload current coming on the system, the existing current thereon for any cause disappears, then the magnet F becomes de-energized and the coiled spring N retracts armature G, H, thus releasing bell crank 35 arm 24 from shoulder L and so accomplish- ing the same result in removing the fuse plugs from their contacts. The fuse strip may lie normally in contact with the oppo- 40 site side of its carrier or be somewhat sepa- rated therefrom so as to be compressed when inserted between the block contacts and so exercise a slight resilient pressure on said contacts.

Ordinarily in switch levers of the knife-type where the lever blade itself, or, as in

the present case, a fuse carrier supported 45 thereon, co-operates with fixed contacts to close circuit, the construction is such that a strong frictional engagement between the blade or fuse carrier and contacts is relied upon to retain the blade in closed position, 50 and obviously in such case a retracting spring capable of lifting the blade cannot be used. Where, however, the blade is held positively in closed position by a latch, as previously described, the frictional engage- 55 ment of blade or fuse carrier and contacts may be slight, and hence easily overcome by the retracting spring, when the latch is released.

We claim:

1. In combination with a movable switch lever, and retracting means therefor, two electro-magnets disposed at an angle one to the other, a latch movable toward either magnet when attracted thereby, and re- 60 tracting means for said latch; the said parts being constructed and arranged so that said latch is moved in one direction by one of said magnets to engage said lever and in another direction by the other of said mag- 65 nets to release said lever.

2. In combination with a movable switch lever, two electro-magnets relatively dis- 70 posed at right angles, an armature common to both magnets, a support for said arma- 75 ture permitting its attraction by either mag- net, two springs respectively opposing the movement of said armature in either direc- 80 tion, and a shoulder on said support engag- ing said switch lever when said support is attracted toward one of said magnets.

In testimony whereof we have affixed our signatures in presence of two witnesses.

THOMAS E. MURRAY.

ARTHUR V. A. McHARG.
